CLAIM

The ornamental design for the hummingbird feeder, as shown and described.

DESCRIPTION

FIG. 1 is a perspective view of the hummingbird feeder, showing the first embodiment of my new design;

FIG. 2 is another perspective view thereof;

FIG. 3 is a front elevational view, the rear elevational view, the left side view and the right side view are identical;

FIG. 4 is a top view thereof;

FIG. 5 is a bottom view thereof;

FIG. 6 is a perspective view of the hummingbird feeder, showing the second embodiment of my new design;

FIG. 7 is another perspective view thereof;

FIG. 8 is a front elevational view and the rear elevational view are identical;

FIG. 9 is a left elevational view and the right elevational view are identical;

FIG. 10 is a top view thereof; and,

FIG. 11 is a bottom view thereof.

The broken lines in the figures are for the purpose of illustrating portions of the hummingbird feeder, which form no part of the claimed design.

1 Claim, 11 Drawing Sheets
